Patented July 9, 1968

211,676

COMBINATION SURGICAL SPONGE AND SUCTION DEVICE

Guiles Flower, Jr., Carlisle, Pa., assignor to
AMP Incorporated, Harrisburg, Pa.

Continuation of design applications Ser. Nos. 6,238, 6,239,
6,241, and 6,242, Mar. 15, 1967. This application Dec.
14, 1967, Ser. No. 10,137

Term of patent 14 years

(Cl. D83—12)

Des. 211,676

PAGE 2

FIGURE 1 is a perspective view of a combination surgical sponge and suction device showing my new and ornamental design;

FIGURE 2 is a side elevational view of the device of FIGURE 1;

FIGURE 3 is a front elevational view of the device;

FIGURE 4 is a rear elevational view of the device;

FIGURE 5 is a bottom plan view of the device of FIGURE 1;

FIGURE 6 is a perspective view of a combination surgical sponge and suction device showing a modified form of the design of FIGURES 1 through 5;

FIGURE 7 is a perspective view of a combination surgical sponge and suction device showing another modified form of the design of FIGURES 1 through 5;

FIGURE 8 is a side elevational view thereof as seen from the right of FIGURE 7;

FIGURE 9 is a front elevational view thereof;

FIGURE 10 is a rear elevational view thereof;

FIGURE 11 is a bottom plan view thereof;

FIGURE 12 is a perspective view of a combination surgical sponge and suction device showing a modified form of the design of FIGURES 7 through 11;

FIGURE 13 is a perspective view of a combination surgical sponge and suction device showing a modified form of the design of FIGURES 1 through 5;

FIGURE 14 is a side elevational view thereof as seen from the right of FIGURE 13;

FIGURE 15 is a front elevational view thereof;

FIGURE 16 is a rear elevational view thereof;

FIGURE 17 is a bottom plan view thereof;

FIGURE 18 is a perspective view of a combination surgical sponge and suction device showing a modified form of the design of FIGURES 13 through 17;

FIGURE 19 is a perspective view of a combination surgical sponge and suction device showing a modified form of the design of FIGURES 1 through 5;

FIGURE 20 is a side elevational view thereof as seen from the right of FIGURE 19;

FIGURE 21 is a front elevational view thereof;

FIGURE 22 is a rear elevational view thereof;

FIGURE 23 is a bottom plan thereof; and

FIGURE 24 is a perspective view of a combination surgical sponge and suction device showing a modified form of the design of FIGURES 19 through 23.

The handle is broken away to show indeterminate length.

This is a continuation of design applications Ser. Nos. 6,238, 6,239, 6,241, and 6,242 filed Mar. 15, 1967, and now abandoned.

I claim:

The ornamental design for a combination surgical sponge and suction device, substantially as shown and described.
